(57) **CLAIM**

The ornamental design for packaging for rolling papers for smoking articles, as shown and described.

DESCRIPTION

FIG. 1 is a top side perspective view of the packaging for

rolling papers for smoking articles showing my new design;

FIG. 2 is a side perspective view from the bottom side thereof;

FIG. 3 is a left side view thereof;

FIG. 4 is a right side view thereof;

FIG. 5 is a front elevation view thereof;

FIG. 6 is a rear elevation view thereof;

FIG. 7 is a top view thereof;

FIG. 8 is a bottom view thereof;

FIG. 9 is a flat, unfolded side view thereof;

FIG. 10 is a top view representing an exemplary rolling paper thereof; and,

FIG. 11 is a straight, folded top view representing an exemplary rolling paper thereof.

The broken line showing rolling portions of the packaging is included for the purpose of illustrating environmental structures and forms no part of the claimed design.
